ELECTROOPTICAL REPRODUCER

John C. Batchelor, Hastings on Hudson, N. Y.

Application August 19, 1937, Serial No. 159,814

7 Claims. (Cl. 178—7.5)

My invention relates to improvements in television scanning devices and the method of operation thereof.

One form of scanning device for television reception comprises a cathode ray tube in which a ray of electrons is focused on a screen and deflected to scan the latter to produce a visible image, the intensity of the ray being varied in accordance with the received picture signals. The image is viewed either directly or is projected and enlarged by a suitable optical system upon a relatively remote screen. In the latter case, the visibility and degree of enlargement of the image depends upon the brilliancy of the image on the screen of the cathode ray tube. Various constructions and methods of operation have been proposed for the purpose of increasing the brilliancy of the image for projection upon a remote screen. One form of such a cathode ray receiving tube is disclosed in British Patent No. 452,368, in which the screen is in the form of a very thin metallic sheet or foil which is scanned by the ray of electrons to heat to luminescence the respective elemental areas of this screen in accordance with the intensity of the ray which is made to vary in accordance with the received picture signals. While this and other forms of construction proposed heretofore have contributed to the possibility of producing an image of great brilliancy for projection, there are still limitations in the size to which the image can be projected on a remote screen, and difficulties are still encountered in producing a sufficiently intense and concentrated electron ray to reproduce a high definition image.

With the foregoing in mind, it is one of the objects of my invention to provide an improved construction and method of operation for a cathode ray scanning device for television reception which, under substantially the same operating conditions, produces on the screen within the tube an image of substantially greater brilliancy than is possible with the various forms of devices proposed heretofore for the same purpose.

Other objects and advantages will appear in the description of my invention which follows.

In accordance with my invention, a cathode ray tube is provided with an image screen, any elemental area of which can be heated to luminescence upon bombardment of such area by electrons focused on the screen. Interposed between this image screen and the electron gun is a thermionic cathode in the form of a screen parallel to the image screen and which is scanned by the electron ray. When the electron ray is

5 directed at any particular elemental area of the cathode screen, this area is substantially instantaneously heated to a temperature corresponding to the intensity of the ray at the instant, as controlled by the picture signals, and electrons are emitted from the side of this area adjacent the image screen and are caused to bombard the adjacent and corresponding elemental area of the image screen to excite the latter to luminescence and to a degree substantially proportional to the ray intensity at the instant. After the ray is deflected away from this elemental area of the cathode screen, electrons still continue to be emitted from the far 10 side of this area until it cools to the temperature at which electron emission ceases, all of which takes place substantially within a picture interval. Because of the fact that there is this substantial increase in the period of time during 15 which electrons from any elemental area of the cathode screen bombard the corresponding elemental area of the image screen, there is a substantial and corresponding increase in the brilliancy of the image on the latter.

20 My invention resides in the improved construction and method of operation of the character hereinafter described and claimed.

25 For the purpose of illustrating my invention, an embodiment thereof is shown in the drawing, 30 wherein:

35 Figure 1 is a simplified, diagrammatic view of a cathode ray tube for television reception, constructed and operating in accordance with my invention;

35 Figure 2 is an enlarged, fragmentary view, taken from Figure 1, and illustrative of the principle of operation; and

40 Figure 3 is a view similar to Figure 1, showing a modification.

45 With reference to the drawing, my improved scanning device comprises an evacuated tube 10 provided with a screen 12 and with means in the form of an electron gun 14 for developing a ray 16 of electrons and directing the ray at the screen 12.

The screen 12 is made of very fine wire mesh and is characterized by the fact that bombardment of any elemental area A thereof by electrons causes such area to be heated to luminescence.

45 Disposed between the electron gun 14 and the screen 12, and closely adjacent the latter, is a thermionic cathode in the form of an electron emissive screen 18 of fine wire mesh. The screen 18 may be made, for example, of fine nickel wire

and may be coated with a mixture of barium and strontium carbonates so that, when heated by the bombardment of the ray 16, the screen 18 will reach a temperature at which electronic emission takes place.

The ray 16 of electrons is deflected horizontally by coils 20 and vertically by coils 22 to cause it to scan the thermionic cathode 18.

The received picture signals are applied to a control grid or electrode 24 with which the electron gun is provided, to vary the intensity of the ray 16 in accordance with these signals.

The ray 16 is focused on the screen 18 by an anode 26 in the form of a metallic coating on the inside surface of the tube 10.

The thermionic cathode screen 18 and the anode 26 are at a potential which is positive with respect to and substantially greater than the potential on the anode 28 of the electron gun, as represented in the drawing, whereby the velocity of the electrons, when they strike or bombard any elemental area of the screen 18, is sufficiently great to cause such area to be heated to a temperature at which electronic emission takes place from the side of this area adjacent the image screen 12, as represented by the arrows 30 in Figure 2. Thus, a thermal image may be said to be deposited on the cathode screen 18 by the cathode ray 16.

The screen 12 is at a potential positive with respect to and substantially greater than the potential of the screen 18, as represented in the drawing, whereby the electrons 30 are caused to strike the screen 12 at a relatively high velocity and heat the elemental area A of this screen to luminescence.

In operation, the brilliancy of any elemental area A of the screen 12 is proportional to that part of the picture interval during which the electrons 30 continue to flow, and also to the mean intensity of these electrons during such time. These two factors are proportional to the temperature to which the adjacent and complementary elemental area of the thermionic cathode 18 is heated upon bombardment of such area by the electron ray 16.

The construction of the screen 18 is such that, for the condition of maximum intensity of the ray 16, the period elapsing before any elemental area of this screen cools to the temperature at which electronic emission therefrom ceases after the ray 16 is deflected away from this area, equals substantially a picture interval. Also, for the condition of maximum intensity of the ray 16, the period elapsing before the elemental areas A of the screen 12 cool to the temperature at which they are not visible due to luminescence, equals substantially a picture interval.

If it is desirable, in any particular case, to space the screens 12 and 18 further apart than is shown in Figure 1, because of the relatively high potential difference between these screens or for any other reason, a focusing coil 34 may be used as shown in Figure 3 to develop an electromagnetic focusing field between the screens 12 and 18 whereby each of the individual rays of the electrons 30 is always directed at and focussed on the corresponding elemental area A of the screen 12. The construction and method of operation in Figure 3 is, otherwise, the same as in Figures 1 and 2.

From the foregoing it will be seen that in my improved scanning device, the brilliancy of any elemental area of the screen 12 is substantially greater, for the same conditions of intensity of

the ray 16, than is the case in devices proposed heretofore for the same purpose, and that this is due to the fact that electronic bombardment of the respective elemental areas of the screen 12 persists or continues after the scanning ray 16 is deflected away from the adjacent and complementary areas of the cathode screen 18. At the same time, image flicker is substantially eliminated.

From the foregoing, one of the broader aspects of my invention may be seen to reside in my improved method of operation which consists in successively exciting the respective elemental areas of a screen, such as the elemental areas A 15 of the screen 12, and during each picture interval varying both the intensity and the duration of excitation of said areas of the screen to produce thereon an image. For example, in the disclosed embodiment of my invention, during each picture interval both the intensity and the duration of excitation of any particular elemental area A vary with and are proportional to both the intensity of the electron ray 30 and the duration of this ray during any picture interval, as 20 controlled or determined by the intensity of the scanning ray or agent 16 at the instant the latter strikes or bombards that elemental area of the screen 18 directly opposite and complementary to the elemental area A of the screen 12.

Another aspect of my invention resides in the heating of the respective elemental areas of a screen to luminescence to produce a visible image on this screen, such as the screen 12, scanning a thermionic cathode for such purpose, such as the cathode screen 18, and controlling the effect of the scanning agent with respect to the thermionic cathode by the received picture signals, the scanning agent of the disclosed embodiment of my invention being the ray 16 of electrons, the intensity of which is controlled by the received picture signals applied to the control grid 24.

Furthermore, it will be seen that in my improved method of operation for television reception, the respective elemental areas of a screen are successively bombarded with electrons such, for example, as the successive bombardment of the respective elemental areas A of the screen 12 with the electrons 30 emanating from the adjacent surface of the thermionic cathode screen 18, and further, that during each picture interval the intensity of the electronic bombardment and the duration of such bombardment on each of said elemental areas are varied to produce an image on the screen comprised of these areas. In the disclosed embodiment of my invention, variation, 45 during each picture interval of the intensity of the bombarding electrons 30 and the duration of such bombardment on each of the elemental areas A of the screen 12 to produce thereon an image, is in accordance with or corresponds to variation in the intensity of the electron ray 16 under control of the picture signals applied to the grid 24.

Considering my improved method of operation for television reception from another viewpoint, it will be seen that it involves the successive heating to luminescence the respective elemental areas of a screen, such as the elemental areas A of the screen 12, and during each picture interval varying both the temperature to which each of said areas is raised and the duration of heating such areas to produce an image on this screen. In the disclosed embodiment of my invention, the temperature to which any particular elemental area A of the screen 12 is

raised during each picture interval is proportional to the intensity of the electron ray 16 at the instant it strikes or bombards the adjacent and complementary elemental area of the thermionic cathode screen 18, and the duration of heating of the elemental area A is proportional to that part of the picture interval elapsing before the adjacent and complementary elemental area of the screen 18 cools to the point whereat the electron emission 30 ceases.

In the construction of my improved scanning device, the screen 18 can be considered as a source of individual electron rays 30 in number equal to the number of elemental areas of the image screen 12 and each serving only one of these areas, the scanning electron ray 16 constituting commutating means for releasing or controlling the effect of the electron rays 30 with respect to the image screen 12.

In cases where the screen 18 might not have sufficient rigidity if it were made entirely of fine nickel wire, it is desirable, for example, either to make the warp of tungsten and the woof of nickel, or vice versa, or to make sufficient of both the warp and woof wires of tungsten to impart the required rigidity to the screen. Other expedients may, of course, be adopted to accomplish this result.

If desired, a thermal bias may be applied to the screen 18 to keep the temperature thereof at least to substantially that at which electronic emission begins to take place from the active surface of this screen. This may be done by heating the screen 18 electrically in any well known manner, by bombarding the screen continuously and uniformly with electrons at the required constant intensity for this purpose, or in any other suitable manner.

It will be understood that the brilliant image produced on the screen 12 may be viewed directly through the transparent end 32 of the tube 10, or projected by a suitable optical system 34 to a remote screen 36 and over an area of the latter many times larger than the area of the screen 12.

For the purpose of improving the steepness of the control characteristic of the scanning device, and speeding up its response to occurring variations in intensity of the cathode ray, a light filter 38 may be placed between the screen 12 and the position from which the image produced on this screen is viewed, or between the screen 12 and the optical system 34 when the image is projected on a larger screen 36. In explanation of the reasons why such improvement is obtained by use of the filter 38, it should be recognized that, as the temperature of a radiating body is increased, the wavelength at which the maximum intensity of radiation occurs shifts successively toward a shorter wavelength, and consequently, the amount of radiation in the shorter wavelength portion of the spectrum will be increased. If, therefore, the filter 38 is so chosen that the longer wavelength portions of the visible spectrum are eliminated from the light produced by the incandescent screen 12, the screen will reach a point of apparent extinction more quickly in the presence of the filter 38 because of the fact that it need cool to a lesser extent to reach such a point when only the shorter wavelengths which are radiated from the screen 12 are used. Without the light filter 38, it would take a given period of time for the elemental area of the screen 12 to cool from the high temperature for white to the lower tem-

perature for dark. However, by using the filter 38, which operates to attenuate the visible light adjacent the long-wave threshold of visibility, the temperature to which the elemental area of the screen 12 must cool before there is no light of incandescence visible, is substantially higher than is the case without the filter. In other words, use of the filter 38 operates to decrease substantially the range of temperature through which any elemental area of the screen 12 must drop to change from a condition of light to dark. It will therefore be apparent that by use of the filter 38, the scanning device is made substantially more responsive to variations in intensity of the cathode ray 16 in accordance with the received picture signals.

In some cases, it may be desirable to substitute for the incandescent screen 12 a fluorescent screen which may be formed directly on the inside surface of the end wall 32 of the tube, or be in the form of a fine wire mesh having fluorescent material applied thereto and filling the interstices therein. Such a form of fluorescent screen is disclosed in my pending application Serial Number 4,494, filed February 1, 1935.

It will be understood that various modifications, within the conception of those skilled in the art, are possible without departing from the spirit of my invention or the scope of the claims.

30 I claim as my invention:

1. In the art of television reception, the method of operation which comprises developing a ray of electrons, controlling the ray intensity by the received picture signals, selectively heating a 35 thermionic cathode with the controlled ray to cause thermionic emission of electrons from the respective elemental areas of said cathode, and utilizing the effect of such thermionic emission from said cathode to heat to incandescence corresponding elemental areas of an incandescent screen to produce a visible image on said screen.

2. In the art of television reception, the steps in the method of operation which consist in developing a ray of electrons, controlling the intensity of said ray of electrons in accordance with received picture signals, utilizing said controlled ray of electrons for selectively heating the respective elemental areas of a thermionic cathode to produce a thermal image thereon and to cause 45 50 55 thermionic emission of electrons from such areas, and utilizing the effect of such thermionic emission from any particular elemental area of said cathode to heat to luminescence an adjacent and corresponding elemental area of an incandescent screen to produce on said screen a visible image.

3. A scanning device for television reception comprising a tube provided with an incandescent image screen the respective elemental areas of which become heated to incandescence upon 60 bombardment thereof by electrons, means for developing a ray of electrons, a thermionic cathode having extended area and being disposed between said ray developing means and said image screen and comprising elemental areas complementary 65 respectively to the elemental areas of said image screen and each constituting a source of electrons for bombarding the respective and corresponding elemental area of said image screen, and means for deflecting said ray of electrons to cause 70 75 the same to scan said thermionic cathode to produce a thermal image on said thermionic cathode.

4. In the art of television reception, the steps in the method of operation which consist in successively heating to incandescence and under control of received picture signals the respective

elemental areas of a screen to produce on said screen a visible image, and at a region between said screen and the position from which the image produced thereon is viewed attenuating the visible light adjacent the long-wave threshold of visibility by an amount substantially greater than the remainder of the visible light is attenuated to produce a modified visible image whose total radiation consists entirely of only a portion of the radiation of said incandescent visible image.

5. In the art of television reception, the method of operation which consists in developing a ray of electrons, controlling the ray intensity by the received picture signals, scanning a cathode with the controlled ray to cause thermionic emission of electrons from the respective elemental areas of said cathode, utilizing the effect of such thermionic emission from said cathode to heat to incandescence elemental areas of a screen to produce a visible image on said screen, and at a region between said screen and the position from which the image produced thereon is viewed attenuating the visible light adjacent the long-wave threshold of visibility by an amount substantially greater than the remainder of the visible light is attenuated.

6. In combination, a scanning device for television reception comprising a tube provided with an incandescent image screen the respective elemental areas of which become heated to incandescence upon bombardment thereof by electrons, means for developing a ray of electrons, means for controlling the intensity of said ray of electrons, a thermionic cathode having extended area

and being disposed between said ray developing means and said image screen and comprising elemental areas complementary respectively to the elemental areas of said image screen and each constituting a source of thermionic electrons for bombarding the respective and corresponding elemental area of said image screen, means for deflecting said controlled ray of electrons to cause the same to scan said thermionic cathode to produce a thermal image on said thermionic cathode, whereby electrons are emitted for bombarding said image screen; and a light filter disposed at a region between said incandescent image screen and the position from which the image produced thereon is viewed and operating to attenuate the visible light adjacent the long-wave threshold of visibility by an amount substantially greater than the remainder of the visible light is attenuated.

7. A scanning device comprising a thermionic cathode having extended area and being capable of emitting electrons in proportion to the temperature of the respective elemental areas thereof, means for producing an electron ray and causing said ray to heat selectively said respective elemental areas of said thermionic cathode to temperatures at which appreciable thermionic emission occurs, and an incandescent image screen adapted to be bombarded by thermionic electrons emitted from said cathode at points substantially corresponding to the points from which said thermionic electrons emerged from said cathode to produce an incandescent image on said image screen.

JOHN C. BATCHELOR.
